UNITED STATES PATENT OFFICE.

WILLIAM COOPER, OF DENVER, COLORADO.

SAFETY-SWITCH FOR THE SPARK-PLUGS OF AUTOMOBILE-ENGINES.

1,250,975.

Specification of Letters Patent. Patented Dec. 25, 1917.

Application filed November 14, 1916. Serial No. 131,252.

To all whom it may concern:

Be it known that I, WILLIAM COOPER, a citizen of the United States of America, residing at the city and county of Denver and 5 State of Colorado, have invented a new and useful Safety-Switch for the Spark-Plugs of Automobile-Engines, of which the following is a specification.

My invention relates to a new safety 10 switch for the spark plugs of automobile engines, and the objects of my invention are:

First, to provide a safety switch that can be applied to the spark plugs of the engines 15 to make or break their circuits to their current supplying apparatus. And

Second, to provide a safety switch that can be operated from the dash board of the car by its driver to connect the spark plugs 20 in circuit with the current supplying apparatus, and can be moved to short circuit and ground the current flowing to the spark gap of the spark plugs, and then be locked in its current shunted or short circuited positions 25 during the absence of the driver from the car, thus making it impossible for any one to start the engine and steal the car during the absence of the driver or owner or when the safety switch is locked.

30 I attain these objects by the mechanism illustrated in the accompanying drawings, in which:

Figure 1 is a plan view of an automobile engine casing, showing the application of 35 the improved switch bar.

Fig. 2 is a side view of Fig. 1.

Fig. 3 is a horizontal sectional view 40 through the switch bar, the said bar being in the position in which its contacts engage the terminal contacts of the spark plugs, thereby to switch or ground the current of the spark plug circuit.

Fig. 4 is a vertical, longitudinal, sectional view through the casing of the switch bar, 45 showing one of the members of the twin non-conducting contact supporting elements broken away to show the recesses which receive the spark plug terminals, the said terminals being shown in engagement with 50 the switch bar contacts.

Fig. 5 is a horizontal, sectional view 55 through the rear end portion of the switch bar, showing the terminal ends of the conductor wires which are electrically connected with the switch contacts, secured to a pin

which extends through the casing of the switch bar.

Fig. 6 is a side view of the switch bar handle and showing the manner of its connection with the switch bar. 60

Fig. 7 is a transverse, vertical, sectional view through the switch bar, and a portion of a spark plug, on the line 7-7 of Fig. 4.

Fig. 8 is a plan view of one of the spark plug conductor plates, to which the wires 65 leading from the spark coil plugs are attached.

Fig. 9 is a transverse, sectional view of a modified form of the switch bar.

Fig. 10 is a sectional view on the line 70 10-10 of Fig. 2. And

Fig. 11 is perspective view of a modified form of spark plug terminal.

Similar letters of reference refer to similar parts throughout the several views. 75

Referring to the drawings,—

The numeral 1 designates the cylinders of an automobile engine, a four cylinder engine being preferably illustrated, and 2 designates their spark plugs, which are arranged 80 in alinement with each other along the length of the engine. These spark plugs may be of any make or kind, but they should be of about the same height, although a little difference in their heights will not interfere 85 with the successful working of my safety switch. 3 designates the dash board that separates the driver's seat from the engine.

My new safety switch consists of a tubular bar 4, which I will term a switch bar when 90 its parts are assembled together in operative condition, although it is composed of a number of different parts. This switch bar is provided with as many socket apertures 5 as there are spark plugs on the engine. Thus 95 the switch bar for the four spark plugs of a four cylinder engine would have four socket apertures, and for the six spark plugs of a six cylinder engine six sockets, and would contain eight and twelve sockets for 100 the eight and twelve spark plugs for eight and twelve cylinder engines, respectively. The socket apertures 5 of each bar are arranged at such distances apart and are of a size to fit loosely down over the top ends of 105 all of the spark plugs of the engine at one time, without engaging the conductive parts of the spark plugs.

In adapting the spark plugs of an engine to receive my safety switch, it is necessary 110

to first remove the top of the binding screw of each spark plug, and screw on it in its place a contact terminal plug head 6, which is a coöperating part of my invention. Each 5 terminal plug head is made of conductive material, and it is made of a size to fit loosely into the socket apertures 5 of the switch bar. Each of these terminal plug heads comprises a shank or neck portion 7, 10 the end of which is provided with a threaded aperture 8, that is adapted to screw onto the top threaded end 9 of a spark plug, and it is arranged and adapted to contact with the current circuit of the spark plug. This 15 plug head is also provided with a cross bar terminal contact portion 10, at its upper end, one end of which is tapered from its opposite sides to an edge to enable it to be wedged between and in contact with oppositely arranged terminal spring blades 11, that are 20 secured within the switch bar to receive the terminal plug head of the spark plug, as will be presently described.

The main switch bar consists of three 25 main parts. The outer member I term the casing 4 of the switch bar, and the inner members I term the cut-outs. The outer casing is reciprocally mounted in guideway bearings 12, that are secured to the top or 30 cylinder head of the engine. The inner cut-outs are made in two strips of the same size and length, and they are made of non-conductive material. These two cut-out strips are held in bearing contact against each 35 other by the tubular casing 4, which fits over them. They are however additionally secured together at their opposite ends by their circuit wires 13, which are twisted together at the ends of the strips to draw and 40 hold them in contact with each other, while the casing is pushed over them from one of their ends. These cut-out bars are composed of two narrow strips, which are made preferably of porcelain, but which may be made 45 of any other non-conductive material, or if desired may be made of two different materials, but they should be made of non-conductive material where the plug heads and switch sockets are located.

50 Each of these cut-out strips is a little longer than the length of the combined distances apart of all of the spark plugs on the engine, and each strip is provided with the same number of longitudinal T-shaped 55 recesses 14, in the lower edge of its inner side, as there are spark plugs on the engine to which these strips are to be applied.

The recesses 14 extend through the bottom edge of each cut-out strip, so that when 60 these strips are placed together, apertures are formed that fit loosely down over the plug head terminal 6 of the spark plugs. The recesses 14 are positioned in the length 65 of these strips so that they will register directly opposite to and fit loosely down over

the plug head contact terminals of the spark plugs.

The socket apertures that form the entrance apertures of the entire switch bar extend down below the cross head top part of the plug heads when the switch bar is placed on them, which allows them to enter fully into the recesses 14, and these recesses 14 are enough longer and larger than the contact terminal cross head part of the plug head to allow the switch bar to be moved reciprocally on them easily by the driver of the car a distance of about three times their length. The longer recess apertures in the cut-outs define the length of this movement, as their rear ends engage the rear ends of the plug heads as the switch bar is moved against them. In one and the same end of each of the recesses 14 of each cut-out strip, a conductive contact terminal 11 is placed. These terminals are secured by a screw 15 directly opposite to each other. Each screw 15 extends through the cut-out strips from their outside surfaces into each recess, and is threaded into the end of the contact terminal switch. These conductive contact terminals are preferably made in the form of strips of spring brass or other suitable spring metal, and each is secured at its inner end to the inner end of the recess and with its free end long enough to form a springing or resiliently yielding contact terminal, and these terminals extend longitudinally along the recess 14 to close to the adjacent edge of the recess 5. The free end 100 of each terminal contact strip is bent down for a short distance from its end in such a manner as to throw the free end portion of the strip up away from the bottom of the recess and form an upward inclined portion of the bent down end portion, thus forming of the two opposite contact terminal switches of each recess when the cut-out strips are in their tubular casing a resiliently yielding double surfaced contact 110 terminal in each recess aperture, which engages the taper pointed end of the terminal cross bar portion of the plug heads, as the switch bar is pushed against them.

The spring contact terminals 11 of each 115 cut-out strip are connected together by a circuit wire 13, which is extended along the outside side surface of each strip in a groove that is formed therein to receive it, and this circuit wire extends under the head of each 120 screw and in contact with each screw and each wire is clamped tight by the head of the screws in its groove. Consequently each 125 of these non-conductive cut-out strips carries a circuit wire, and when the two are held together in the casing their circuit wires, which extend to their ends, are twisted together at the opposite ends of the cut-out strips, thus forming a continuous circuit 130 from one wire to the other, and consequently

from each pair of terminal contact springs in each aperture recess or from only one of these springs, in case only one of them should engage the cross bar contact terminal 5 of a spark plug in any of the recesses. These two cut-out strips are connected together with their recesses facing each other by screws 16, which extend through them and are arranged to clamp them together, with 10 their recesses and switch springs registering opposite to each other. They are then inserted in the tubular casing with their recesses 5^a registering with the apertures 5 in the bottom of the casing. The casing is 15 then secured to them by a screw 17 that extends through the casing and the cut-outs. The circuit wires 13 are preferably bare copper wires and their ends after being arranged to bear against the casing or against 20 the cap 19 at one end of the switch bar, may be secured to or placed in bearing contact against a plug 18 that is secured in the dash board end of the switch bar. I preferably however connect them directly to the casing 25 at the outer ends of the cut-out strips after they are twisted together by twisting their ends around a pin 20 that is extended through the end of the casing 4 before the cap 19 is secured on its end. The cap 19 is 30 secured to the end of the pipe by a screw 21. The plug 18 extends loosely into the end of the casing nearest to the dash board, and this plug is provided with a central slot in which is inserted loosely and is detachably secured one end of a handle 22. The handle 22 is detachably secured to the plug by any suitable means, as it is necessary to remove it when removing the switch bar 35 from the spark plugs when removing one or 40 more of them from the engine.

I preferably however secure the plug and handle to the casing by screw driver screws 23 which are extended through the casing from one side and pass loosely through the 45 plug and handle, and are threaded into the opposite side of the casing.

This detachable handle extends loosely through a boss 24 that is secured to the dash board. This boss has a hub that projects 50 from the inside of the dash board, and the handle is arranged to be locked to either the boss or its hub or to the dash board in any suitable manner or by any suitable lock or locking mechanism, when the switch bar is 55 pushed into circuit contact with the cross bar heads 6 of the spark plugs.

I preferably however lock the switch bar in this closed circuit position with the heads of the spark plugs in the following manner: 60 A finger ring 25 is formed in the end of the handle to enable the driver to grasp it and pull and push it, and two apertures 26 and 27 are formed through it. An aperture 28 is also formed through the hub of the 65 boss. One of the two apertures 26 and 27

in the handle is positioned to be in alignment with the aperture through the boss, when the switch bar is pushed forward through the dash board's boss until its spring contact terminals 11 are wedged against the opposite sides of the taper ends of the cross bar of the plugs, and then the bow portion 29 of a padlock 30 is placed through the alined apertures in the hub and handle and the padlock is locked to them. 70

When the switch bar is pulled toward the dash, the contact springs move away from the plug heads and they occupy the rear non-conductive port of the recesses 14, and the other aperture 27 in the handle is then 80 in alinement with the aperture in the boss and the padlock can be placed through them and the switch bar is then secured out of circuit with the cross bars of the spark plugs. 85

The plug heads of the spark plugs are 85 connected by circuit wires 31 to the plugs 32 of the dash board by any suitable means, such as twisting them around the necks of the plug heads, but I preferably remove the plug heads and place an apertured conductive plate 33 over the small end of each spark plug and clamp the plate there by the plug head. 90

The outer ends of these plates are provided with apertures 34, through which the 95 ends of these circuit wires are placed and are twisted to secure them to the plates. After the circuit wires are connected to the spark plugs the switch bar is mounted on their plug heads; in order to do this, however, the handle has to be removed from the plug 6 of the switch bar, pushed through the dash board, and connected to the switch bar, after the switch bar is mounted on the heads of the plugs. 100

The electric circuit wires are then connected to the plates of the spark plugs, and the circuit is complete from the source of current supply, to which the plugs 32 are connected, to the spark plugs and to the 110 spark gap of the spark plugs, when the cross bars are not in contact with the spring switches of the switch bar.

The spring switch circuits in the switch bar are grounded to the casing and any current that passes into them from the cross bars of the spark plugs is grounded through the casing and the guides to the engine. No current, however, can pass from the cross bars of the spark plugs except when the cross bars of the spark plugs are engaged by the spring circuits of the switch bar, and this can take place only when the switch bar is moved by the driver of the car to cause the switch springs to engage the cross bars of 115 the spark plugs in its sockets, which contact causes the current to shunt or short circuit from the plates 33 of the spark plugs through their cross bars and the switch springs into the circuit wires 13, and from 120 125 130

them to flow through the casing and guides to the engine, in which it grounds or passes to the magneto or generator.

The operation is as follows:

Assuming that the driver of a car to which my safety switch has been applied, short circuited it to the cross bars of the spark plugs and locked it to the boss of the dash board when he stopped the engine and left his car. Then the first thing he does on entering the car is to unlock the padlock, remove it from the boss, and then draw the switch-bar toward him as far as it will go, which movement disengages the terminal spring switches from the cross bars of the spark plugs, thus breaking the short circuit and leaving the spark plugs entirely free and separated at a space apart from the spring contact terminals, so that the electric current when turned on flows from the plugs 32 through the circuit wire to the spark plugs and it will flow through the spark plugs as soon as it is turned on and will operate the engine, which the driver can run as he desires and stop and start it when he desires without touching the switch bar until he is ready to leave the car and when he desires to leave and lock it, so that no one can turn the current on and start the engine. He removes the padlock and pushes the switch bar forward as far as it will go, which moves the spring contact terminals into engagement with the cross bars of the spark plugs, and should the current be turned on by any one it is shunted or short circuited from the cross bars through these spring contacts, and their circuit wires, and flows through the casing and guides and grounds in the engine through which it flows to the magneto or other circuit generating apparatus of the car. Consequently by means of my safety switch it is impossible for any one to start the engine and steal the car by turning on the sparking current, as the current would be immediately short circuited away from the tops of the spark plugs and could not flow to their gap sparking and explosive mixture igniting ends.

Another important feature of my invention is that when the handle is locked to the boss of the dash, the switch bar can not be removed from the plug heads of the spark plugs even if the handle is disconnected from it by removing the screws from it, and the inner end of the handle. The handle must be unlocked first from the boss of the dash before the switch bar can be removed to cause its recesses 5 to register with the plug heads, so that the switch bar can be lifted from them.

Where an engine has cups at the side of the spark plugs, the plug terminals are made with an offset in their necks, as shown in Fig. 11, so that the switch bar will stand to one side of the cups.

My invention provides a simple, inexpensive and reliable safety switch for automobile engines, that renders it impossible for any one to start the engine without unlocking and moving the switch to allow the current when turned on to flow to the spark gap of the plugs.

While I have illustrated and described the preferred construction and arrangement of my invention, I do not wish to be limited to it, as many changes might be made without departing from the spirit of my invention.

Having described my invention, what I claim as new and desire to secure by Letters Patent, is:

1. In a safety switch for the operatively connected spark plugs of automobile engines having the combination with the engine and dash board, of the spark plugs having a conductive terminal contact in their circuits, at their top ends, a switch bar provided with recesses arranged to fit down over said plugs' terminal contacts and move reciprocally thereon, contact terminals in one end of said recesses adapted to engage said plugs' terminal contacts when said switch bar is moved in one direction of its reciprocal movement, a non-conductive space for said plugs' terminal contact in each recess when said switch bar is moved in the opposite direction of its reciprocal movement, means for reciprocally supporting said switch bar, means including circuit wires for grounding the contact terminals in said recesses, a handle portion on said switch bar extending slidably through said dash, and means for locking said switch bar to said dash in circuit contacting relation with and out of circuit contact with said plugs' terminal circuit contacts.

2. In a safety switch for the spark plugs of automobiles, the combination of the engine, the spark plugs and the engines, a cross-bar terminal on each spark plug, a switch bar provided with non-conductive socket recesses adapted to fit over and move reciprocally on said plugs' terminal contacts, a pair of spring contact terminals in one end and the same end of each switch bar's recesses arranged to engage said plugs' terminals on one stroke of said switch bar's reciprocal movement, and to be moved out of contact on the other stroke of its reciprocal movement, a tubular casing surrounding said switch bar having apertures leading into its plug head receiving recesses, circuit wires from said spring contact grounded in said casing, supporting guides on said engines for said switch bar, a boss on the inside of said dash, a handle detachably connected to said switch bar and extending through the boss of said dash, an aperture through said boss, apertures through said handle arranged to register with the aperture in said boss when said switch bar is

5 moved into circuit contact with said plugs' terminal cross bars and when it is out of circuit with the same, and means including a padlock for locking said switch bar to the boss of said dash in either of these positions as desired.

3. In a safety switch for the electrically connected spark plugs of automobile engines, the combination with the dash and the engines, of the spark plugs provided with a conductive cross-bar form of terminal contacts, and the short circuiting switch bar reciprocally mounted on said plug terminals and connected to said dash, and means for locking said switch-bar to said dash in short circuited contact with said plugs' terminals and out of circuit contact with said plugs' terminals.

4. In a safety switch for the electrically connected spark plugs of automobile engines, the combination with the dash and the engines, of the spark plugs provided with a conductive cross-bar form of terminal contacts and the short circuiting switch bar reciprocally mounted on said plug terminals and connected to said dash, said switch bar comprising the pair of cut-out strips, provided with the registering T-shaped plug terminal receiving recesses, the tubular casing surrounding said cut-out strips and provided with apertures registering with the recesses of said cut-out strips, the spring blade contact terminals secured on opposite sides of one and the same ends of said recesses, the circuit wires on said cut-out strips connected to said switches and grounded to said casing, the guides for reciprocally supporting said switch bar on said engine and plug terminals, a handle on said switch bar extending through said dash, and means including a padlock for locking said switch-bar to said dash in short circuited contact with said plugs' terminals and out of circuit contact with said plugs' terminals.

45 5. In a safety switch for the electrically connected spark plugs of automobile engines, the combination with the dash and the engines, of the spark plugs provided with a conductive cross-bar form of terminal contacts and the short circuiting switch bar reciprocally mounted on said plug terminals and connected to said dash, said switch bar comprising the pair of cut-out strips, provided with the registering T-shaped plug terminal receiving recesses, the tubular casing surrounding said cut-out strips and provided with apertures registering with the recesses of said cut-out strips, the spring blade contact terminals secured on opposite sides of one and the same ends of said recesses, the circuit wires on said cut-out strips connected to said switches and grounded to said casing, the guides for reciprocally supporting said switch bar on said engine and plug terminals, a handle on said switch bar

extending through said dash, and means for securing said cut-out strips together and for securing said casing to said cut-out strips and for detachably securing said handle to said switch bar.

6. In a safety switch for the spark plug of automobile engines, the combination with the engine and dash and the spark plugs of automobiles, said spark plugs being provided with the cross-bar terminal conductive contact heads, of the spark plugs of the switch bar comprising the casing, the cut-outs and their plug head surrounding recesses, the spring blade contact terminals and their circuit wires, the handle extending through the dash, and means for reciprocating and locking said switch bar to said dash in operative short circuiting engagement with said terminal conductive contact plug heads and out of circuit with them.

7. In a safety switch for the spark plug of automobile engines, the combination with the engine and dash and the spark plugs of automobiles, said spark plugs being provided with the cross-bar terminal conductive contact heads, of the spark plugs of the switch bar comprising the casing, the cut-outs and their plug head surrounding recesses, the spring blade contact terminals and their circuit wires, the handle extending through the dash, and means for reciprocating and locking said switch bar to said dash in operative short circuiting engagement with said terminal conductive contact plug heads and out of circuit with them, and means for reciprocally supporting said switch bar, and means including a conductive connection between said spring contacts of said cut-outs arranged to ground said short circuited current from the terminal heads of said spark plugs to said engine.

8. The combination with the spark plugs of an internal combustion engine, an electric current source, and wires connecting said plugs and current source, of slidable means connected with and housing the terminal ends of said spark plugs for diverting the current to said plugs, when in one position, and permitting the flow of the current to said plugs when in another position.

9. The combination with the spark plugs of an internal combustion engine, an electric current source, and wires connecting said plugs and said current source, of a recessed bar slidably mounted on said plugs having contacts which engage said plugs in one position of the bar, and which are out of engagement with said plugs when the bar is shifted, and conducting elements connected with said contacts for diverting the current to said plugs when said plugs are engaged by said contacts, said recesses being adapted to house the terminal ends of said plugs.

10. The combination with the spark plugs

of an internal combustion engine, an electric current source, and wires connecting said plugs and said source, of terminal blocks mounted on the center poles of said plugs, a 5 recessed bar slidably mounted on said blocks having contacts which engage said blocks in one position of the bar and which are out of contact with said blocks when the bar is shifted, and conducting elements connected 10 with said contacts for diverting the current to said plugs when said blocks are engaged by said contacts, said recesses being arranged to house said blocks.

11. The combination with the spark plugs 15 of an internal combustion engine, an electric current source and wires connecting said plugs and said current source, of terminal blocks connected to the poles of said spark plugs, a bar slidably mounted on said ter-

20 minal blocks comprising an outer metal casing, and a non-conducting core, contacts in said core for engaging said blocks in one position of the bar, and which are out of contact with the blocks when the bar is shifted, 25 conducting elements connecting said contacts with the metal casing, and metal slideways on said engine in which said casing is mounted, whereby when the said contacts engage said blocks the current flowing to 30 said plugs is diverted, and means for locking said bar in either position.

In testimony whereof I affix my signature in presence of two witnesses.

WILLIAM COOPER.
